CLAIM

The ornamental design for a string dispenser or similar article, substantially as shown and described.

DESCRIPTION

FIG. 1 is a perspective view of a string dispenser or similar article showing my new design;

FIG. 2 is a front elevational view thereof, the rear elevational view being a mirror image of the front;

FIG. 3 is a right side elevational view thereof, the left side elevational view being the mirror image of the right; and

FIG. 4 is a top plan view thereof, the bottom plan view being the mirror image of the top.

FIG. 1

FIG. 2

FIG. 3

FIG. 4
